UNITED STATES PATENT OFFICE

100,970

DESIGN FOR A FOUNTAIN PEN OR SIMILAR ARTICLE

Milford Guy Sypher, Belleville, N. J., assignor to
The Chilton Pen Company, Inc., Long Island
City, N. Y., a corporation of New York

Application July 21, 1936, Serial No. 63,968

Term of patent 14 years

To all whom it may concern:

Be it known that I, Milford Guy Sypher, a citizen of the United States, residing in Belleville, county of Essex, State of New Jersey, have invented a new, original, and ornamental Design for a Fountain Pen or Similar Article, of which the following is a specification, reference being had to the accompanying drawing forming a part thereof.

The figure is a front elevational view of a fountain pen showing my new design.

The dominant feature of my design is the ornamentation, substantially as shown, applied to fountain pens or similar articles.

I claim:

The ornamental design for a fountain pen or similar article substantially as shown and described.

In witness whereof, I have hereunto affixed my hand this 29th day of June, 1936.

MILFORD GUY SYPHER.
